The ornamental design for a trash can as shown and described.

USPC **D34/7**

DESCRIPTION

(58) **Field of Classification Search**

FIG. 1 is a front, right and top perspective view of a trash can, showing my new design.

CPC B65F 1/00; B65F 1/0013; B65F 1/002; B65F 1/004; B65F 1/0033; B65F 1/163; B65F 1/1638; B65F 1/1421; B65F 1/1426; B65F 1/16; B65F 1/122; B65F 2001/1489

FIG. 2 is a rear, left and bottom perspective view thereof.

See application file for complete search history.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the trash can that form no part of the claimed design.
